UNITED STATES PATENT OFFICE.

WILLIAM E. ALMES, OF RACINE, WISCONSIN.

VACUUM TANK FOR CARBURETORS.

Application filed April 5, 1921. Serial No. 458,850.

To all whom it may concern:

Be it known that I, WILLIAM E. ALMES, a citizen of the United States, and resident of Racine, in the county of Racine and State of Wisconsin, have invented certain new and useful Improvements in Vacuum Tanks for Carburetors; and I do hereby declare that the following is a full, clear, and exact description thereof.

10 This invention relates to a new and improved vacuum tank which is primarily designed to be used in connection with a carburetor for internal combustion engines.

The object of the invention is generally 15 to so construct a tank of this kind that the gasoline or other liquid fuel will be fed uniformly to the float chamber of the carburetor while the engine is running.

A further object of the invention is to 20 provide a vacuum chamber in which the fuel is prevented from feeding into the float chamber when the engine is stopped, and thereby flooding the carburetor.

With the above and other objects in view, 25 which will be apparent from the foregoing description, my invention resides in the details of construction which are shown in the accompanying drawing, the single figure of which represents a vertical sectional view 30 through the float chamber and the vacuum tank attached thereto.

Referring in detail to the drawing, the numeral 1 designates the float chamber which is connected in the usual manner to 35 the mixing chamber 2 of the carburetor, the usual drain cock 3, being provided in the bottom of the float chamber. The fuel is fed into the float chamber 1 through the inlet opening 4, the lower end of which 40 is controlled by the conical valve 5 which is operated by a float 6. A U-shaped strap 7 is attached to the cover of the float chamber, and supports the float 6 which has a stem 8 slidably mounted in the horizontal 45 portion of the strap.

The cover of the float chamber is in the present instance made as an integral part of the vacuum tank 9, which is in turn provided with a cover 10. The interior of the 50 tank is normally in communication with the vacuum pump through the passageway 11, and as the pump is operated to produce a vacuum, the fuel is drawn in through the inlet 12. The fuel in the tank 9 is main-

tained at subsequently constant level by the 55 float 13, which is carried by a stem 14 which projects downwardly, and has a conical valve 15 which seats on the mouth of the opening 4 which leads into the chamber 1.

Projecting upwardly from the float 13, 60 is a stem 16 which is provided with a conical surface 17, adapted under certain conditions, to close the passageway 11 leading to the vacuum chamber. The stem 16 is also provided with a reduced end portion 18 65 which cooperates with the ball valve 19 to put the vacuum chamber into communication with the atmosphere through the port 20.

Means are provided, as shown at 21, for 70 adjusting the length of the stem which carries the float 13. It will be noted that the chamber 1 is normally closed to the atmosphere except for a small bleed hole 22.

Starting with the parts in the position shown in the drawing, when the engine is 75 started a partial vacuum will be created in the chamber 9 which will draw the fuel in through the inlet 12, raising the float 13 until the conical surface 17 closes the passageway 11 and simultaneously the reduced 80 portion 18 raises the ball valve 19 to admit atmosphere through the port 20 into the tank. This stops the flow of fuel into the tank 9, and at the same time raises the valve 15 to admit fuel through the opening 4 into 85 the float chamber 1. The fuel thereupon runs into the chamber 1 by gravity until the float 6 and valve 5 are raised to cut off the flow of fuel.

As soon as the fuel commences to run 90 from the tank 9, to the chamber 1, the level of the fuel in the tank is lowered thereby closing the valve 19 and opening the passageway 11 whereupon the vacuum again comes into operation. When the engine 95 stops running, the float 13 will immediately be lowered and the valve 15 will close the opening 4 and prevent any more fuel from leaking into the float chamber 1, and thereby causing the carburetor to become flooded. 100

From the foregoing description it will be seen that I have constructed a vacuum tank by which the flow of fuel into the float chamber will be uniform and constant under all conditions.

While I have shown and described one specific form in which my invention may be embodied, it will be understood that many 105

modifications may be made within the scope of what is claimed without departing from the spirit of the invention.

I claim:

- 5 1. In a carburetor, a float chamber, a float therein, a vacuum tank having a wall closing said float chamber and provided with an aperture having two valve seats, a valve operated by said float and cooperating with one of said valve seats, a float in said vacuum chamber, a valve operated by said last mentioned float and cooperating with the other of said valve seats, and means actuated by said last mentioned float for controlling the pressure in said vacuum tank.
- 10 2. In a carburetor, a container having an upper and a lower compartment separated

by a dividing wall provided with an aperture therethrough, a float mounted within the lower compartment, a valve means operated by said float for controlling the flow of fuel through said aperture, vacuum and fuel supply means communicating with the upper compartment, a float mounted in the upper compartment and having upwardly and downwardly projecting spindles, valve members carried adjacent the upper and lower portions of said spindles and respectively controlling the vacuum means and the flow of fuel through said aperture. 20 25

In testimony that I claim the foregoing I have hereunto set my hand at Racine, in the county of Racine and State of Wisconsin. 30

WILLIAM E. ALMES.
